UNITED STATES PATENT OFFICE.

EDWARD H. J. DILLON, OF PHILADELPHIA, PENNSYLVANIA, ASSIGNOR TO THE GRIS-COM-RUSSELL COMPANY, A CORPORATION OF DELAWARE.

STORAGE HEATER.

Application filed June 19, 1920. Serial No. 390,237.

To all whom it may concern:

Be it known that I, EDWARD H. J. DILLON, a citizen of the United States, residing at Philadelphia, in the county of Philadelphia, 5 State of Pennsylvania, have invented certain new and useful Improvements in Storage Heaters; and I do hereby declare the following to be a full, clear, and exact description of the invention, such as will 10 enable others skilled in the art to which it appertains to make and use the same.

This invention relates to storage heaters of the kind employed for supplying hot water or other liquid in quantity, and particularly 15 storage heaters of this kind in which the heat is indirectly supplied, as by the condensation of steam in tubes projected into the shell forming the storage tank for the liquid to be heated.

20 The principal object of the invention is to provide a heater of this character in which the heating tubes forming the so-called tube bundle may be readily withdrawn from the storage shell for cleaning or repair by one 25 or two men notwithstanding the weight and bulk of the tube bundle.

In storage heaters of comparatively large capacity, particularly where exhaust steam is used as the heating medium and there is 30 consequently but a small difference between the steam and the temperature to which the water is to be raised, the necessary tube surface is large, and if the water to be heated is of a scale-forming character the tubes 35 must be cleaned at frequent intervals to obtain efficient operation. In such heaters as now constructed it is a difficult task to remove the heavy bulky tube bundle without damage to the tubes or the bolts and packing 40 gasket employed between the tube supporting sheet and wall of the shell. According to my invention, I support the tube bundle in such a manner that it may be withdrawn to a sufficient extent without lifting or suspending the weight of the tube bundle for the 45 tubes to be readily cleaned, and may then be guided in its return movement in such a manner as to position the tube supporting sheet accurately on its seat without damage 50 to the latter.

In the accompanying drawings I have illustrated a preferred embodiment of the invention, and a modification adapted for different styles of heaters.

Referring to the drawings;

Fig. 1 is a side view of a storage heater, the tank being broken away, the tube bundle being sectioned;

Fig. 2 is a view showing the tube bundle drawn out of the tank;

Fig. 3 is an end view;

Fig. 4 is a view similar to Fig. 1 showing a modification; and

Fig. 5 is a view of line 5—5 of Fig. 4.

The tank for the heating and storage of 65 the hot water is indicated at 1, and is preferably arranged in a horizontal position. One end of the tank is provided with an opening 2 through which the tube bundle is adapted 70 to move. This opening is reinforced by an 70 annular ring 3. The tube bundle, indicated at 4, comprises a number of horizontal tubes supported at their inner ends by the plate 5 and at their outer ends by the plate 6. A dome-shaped cap 7 is mounted on the plate 75 5, the space within the cap being in communication with the ends of the several tubes of the tube bundle. The cap is provided with a supporting arm 8 which is inclined 80 downwardly and outwardly as shown. The arm is provided with a roller 9 that moves on the track 10, positioned inside the tank and longitudinally thereof. Associated 85 with the supporting plate 6 is a cap plate 11, these two plates being shaped as shown in Fig. 1 to accommodate themselves to the angle of the end of the heater. Plates 6 and 11 are provided with recesses which 90 register to form the steam inlet chamber 12 to which steam is led by the inlet pipe 13.

At the outer end of the tube bundle are two supporting arms 14 which are screw threaded, and which engage with standards 15 on the plate 11 and with adjusting nuts 16, so that the outer end plates of the tube 95 bundle may be adjusted for accurate seating in the end of the storage tank. The arms 14 are provided with rollers 17 which move on tracks 18 so as to support the outer end of the tube bundle during its movement into 100 and out of the tank. Suitable gaskets or other leak-preventing devices may be used as desired.

The heating medium, which may conveniently be exhaust steam, enters through the 105 pipe 13, is distributed through the tubes of the tube bundle and passes into the space within the cap 7, thus heating the water within the

2
tank and itself being condensed. The condensed steam escapes through the pipes 19 and 20. Tank 1 is provided with an inlet pipe 21 for cool water and an outlet pipe 22 for hot water.

The modification shown in Fig. 4 shows the invention as applied to a somewhat different form of tube bundle, the tube bundle in this instance being composed of a number 10 of U-shaped tubes 23, the inlet and outlet ends of which respectively communicate with inlet and outlet chambers 24 and 25 formed by cooperation of the outer end plates 26 and 27. The inner end of the tube bundle is supported by a plate 28, which in turn is supported by a downwardly and outwardly inclined arm 29 provided with a roller 30 movable on the track 10.

From the constructions that have been described it will be apparent that the tube bundle may be moved well out of the tank so as to be accessible for scaling and repairs, both ends of the tube-bundle being supported during the entire movement of the bundle. Any sagging of the inner end of the bundle is to be avoided, because it prevents accurate seating of the outer supporting plate and makes the in and out movement of the tank difficult. By virtue of the fact 30 that the inner end of the tube bundle is always supported, there is no tendency, when the bundle is half way out or all the way out of the tank, for that end of the bundle to sag. Moreover, when the bundle is all the 35 way in the tank in normal position the inner end of the bundle will not sag, resulting in the accurate seating of the outer end plate. With the supporting arms 8 and 29, as the case may be, inclined as shown, the tube bundle is projected well out of the tank so that 40 all parts of it are completely accessible, while at the same time the support for the inner end is still resting on the track inside of the tank.

45 While I have illustrated two supports for the outer end of the bundle and one support for the inner end, it, of course, should be understood that this arrangement might be reversed, or that various other supporting devices for the ends of the tube bundle might be used. It shuold also be understood that other parts of the apparatus are not limited to the precise structure shown, but may be embodied in other forms, as falling within 50 the scope of the following claims.

55 It is also to be understood that while the apparatus has been described as a water heater, it is not limited to such use, but may obviously be employed for other purposes, 60 and the invention is in no wise limited to the use of the apparatus for heating water.

I claim:

1. In a water heater, the combination of a tank, a tube bundle movable into and out of

the tank, means located within the tank to 65 support the inner end of the tube bundle during its movement, said means comprising a supporting element associated with said bundle and contacting with the stationary portion of the tank at a point materially beyond 70 the end of said bundle, and means to support the outer end of the bundle.

2. In a water heater, the combination of a tank, a horizontal tube bundle movable into and out of the tank, a track within the tank, 75 a track outside the tank, means supporting the inner end of the tube bundle movable on the inner track, said means permitting the entire tube bundle to be removed completely to the exterior of the tank; and means supporting the outer end of the tubes, said bundle being movable on the outer track.

80 3. In a water heater, the combination of a tank, a horizontal tube bundle movable into and out of the tank, means to support the 85 outer end of the bundle during its movement, an inclined supporting arm to support the inner end of the tube bundle, and a track located within the tank, on which the inclined supporting arm moves.

90 4. In a water heater, the combination of a tank, a horizontal tube bundle movable into and out of the tank, means within the tank to support the inner end of the tube bundle, and means to support the outer end of the tube bundle, said means comprising threaded supporting members and nuts on said members, whereby the height of the outer end 95 of said tube bundle may be changed by altering the position of said nuts.

100 5. In a water heater, the combination of a tank, a heating element movable into and out of the tank, and means within the tank to support the inner end of said heating element, said means comprising a supporting bracket projecting inwardly beyond the inner end of the heating element whereby the entire heating element may be withdrawn from the tank without withdrawing the support from the tank.

110 6. In a water heater, the combination of a tank, a heating element movable into and out of the tank, and means within the tank to support the inner end of said heating element, said means comprising a supporting bracket projecting inwardly beyond the inner end of the heating element whereby the entire heating element may be withdrawn from the tank without withdrawing the support from the tank, a roller carried by 115 said bracket adapted to roll along the bottom of said tank and a supporting roller attached to the other end of the heating element and adapted to support the outer end of the heating element as the heating element is withdrawn from the tank.

In testimony whereof I affix my signature,
E. H. J. DILLON.
